UNITED STATES PATENT OFFICE.

KONRAD JAGSCHITZ, OF MAINZ, GERMANY, ASSIGNOR TO MASCHINENFABRIK AUGSBURG-NUERNBERG, A. G., OF NUERNBERG, BAVARIA, GERMANY, A CORPORATION OF GERMANY.

FOUNDATION FOR DRY GASOMETERS.

Application filed December 26, 1923. Serial No. 682,841.

To all whom it may concern:

Be it known that I, KONRAD JAGSCHITZ, a citizen of the Republic of Germany, residing at No. 27 Weintorstrasse, Mainz, Germany, have invented certain new and useful Improvements in Foundations for Dry Gasometers, of which the following is a specification.

This invention relates to dry gasometers and more particularly to the foundations thereof; its main object is the provision of means to easily and quickly right the gasometer upon its foundation in case it should subside owing to being built on bad ground, or in the mining areas, where sagging of the ground is of frequent occurrence.

It is an admitted fact that dry gasometers can withstand one-sided sagging of the ground, i. e. one-sided inclinations of their structures only to a very slight extent, and the invention, therefore, provides an arrangement, by means of which the gasometers may be righted in a most simple and efficient manner without in the least affecting their stability.

According to the invention the gasometer is erected upon a base plate of concrete or the like adapted to carry the inner useful load, and which rests with its outer circumference upon an annular foundation, herein-after called the foundation ring, of concrete or the like, which is provided with an insulating surface layer and by which the weight of the gasometer is supported and the forces set up by wind pressure, and others, are resisted. The arrangement according to the invention is such that the foundation or base plate carrying the gasometer is placed over the said ring and detachably connected thereto by means of foundation bolts, and that lifting devices are spaced at certain intervals around the circumference of the said ring and in contact with the base plate. Thus, should a sinking occur, the gasometer need only be lifted at the respective place or places by means of the lifting devices, whereupon the clearance may be filled up with concrete.

The accompanying drawings diagrammatically illustrate the invention by way of example.

Fig. 1 is a vertical section through a gasometer having a foundation constructed according to the invention;

Fig. 2 a plan view of the foundation or base plate; and

Fig. 3 is a detail view illustrating the lifting and securing devices.

In the drawings the gasometer which is denoted by 1 is erected upon a foundation or base plate 3 of concrete or other suitable material which is braced by ribs 2 and adapted to rest with its circumference upon a foundation ring 4 which is likewise made of concrete or the like material. The said foundation ring 4 is provided with a surface layer 5 of insulating material. The base plate 3 is provided with extensions 6 of the ribs 2 at the places corresponding to the corners of the gasometer, and below these extensions, which project beyond the circumference of the ring 4, lifting screws 8 are arranged upon lugs 7 extending from the ring 4 and by means of which the gasometer may be raised at such places where the ground may have given way, whereupon the spaces intermediate the extensions may be filled up with concrete. Foundation bolts 9 are provided to detachably connect the plate 3 to the ring 4.

It is evident that other lifting means may be employed instead of the screws 8, which latter, however, constitute a preferred form of lifting arrangement on account of their simplicity and ease of manipulation.

What I claim is:—

1. In a foundation for dry gasometers the arrangement of a base plate carrying the gasometer, a foundation ring engaging said base plate near its circumference from below to support the same, and means between the said base plate and the foundation ring to enable a one-sided raising of the base plate and the gasometer erected thereon.

2. In a foundation for dry gasometers in combination a strengthened base plate, a foundation ring supporting said base plate, lifting means between the base plate and engaging the same from below and the foundation ring spaced around the circumference thereof, said lifting means adapted to enable a one-sided raising of the base plate and the gasometer erected thereon.

3. In a foundation for dry gasometers in combination a base plate strengthened by ribs, extensions of the base plate spaced around its circumference, a foundation ring engaging said base plate from below to sup-

port the same, lugs projecting radially outward from the foundation ring in registry with and below the said extensions, lifting means upon the said lugs and bearings 5 against the extensions, and foundation bolts to detachably connect the base plate to the foundation ring.

4. In a foundation for dry gasometers in combination a base plate, a foundation ring 10 engaging said base plate near its circumference from below for supporting the same, and lifting screws between said foundation ring and the base plate spaced around the circumference thereof.

15 5. In a foundation for dry gasometers in combination a base plate, ribs to strengthen the said base plate and extending into flat portions projecting radially outward from

the base plate, a foundation ring engaging said base plate from below, lugs projecting 20 from the foundation ring in registry with and below said flat portions, lifting screws arranged upon the lugs and bearing with their upper ends against the said flat portions of the base plate, an insulating surface 25 layer on the foundation ring beneath said base plate, and foundation bolts to detachably connect the base plate to the foundation ring.

In testimony whereof I affix my signature in presence of two witnesses.

KONRAD JAGSCHITZ.
